AGITATOR FOR WASHING MACHINES

Jabez Curry Nelson, Syracuse, N. Y., assignor to
Easy Washing Machine Corporation, Syracuse,
N. Y., a corporation of Delaware

Application January 9, 1936, Serial No. 58,393

7 Claims. (Cl. 68—54)

My invention relates to washing machines and, more particularly, to a novel agitator or dolly therefor.

An object of my invention is to provide an agitator adapted to be mounted in a vat containing clothes and washing fluid for oscillation therein, said agitator being provided with means for alternately raising and depressing the body of clothes in the vat.

10 Another object of my invention is the provision of an agitator adapted to be oscillatably mounted in a vat containing clothes and washing fluid, the agitator including means for alternately raising and depressing the body of clothes in the vat and, during such raising and depressing operation, subjecting the fabrics to a scrubbing and thread-deforming action.

20 My invention further contemplates the provision of an oscillatable agitator adapted to be mounted in a vat containing clothes and washing fluid, the agitator having means for alternately raising and depressing the fabrics, subjecting them to a scrubbing action and causing the clothes and washing fluid to circulate in one resultant circulatory direction around the vat, whereby the clothes periodically change their relative positions and the entire body of the clothes, at some time during the washing cycle, is subjected to the scrubbing and thread-deforming 25 action of the agitator.

30 More specifically, my invention contemplates the provision of an agitator for a washing machine having a substantially flat plate of relatively large area mounted at an angle to the horizontal which, when the agitator is oscillated, causes the clothes to be alternately raised and depressed, said agitator also being provided with a plurality of scrubbing ribs adapted to exert a substantial thread-deforming action on the clothes and also adapted to cause the clothes to circulate predominantly in one direction around the vat.

35 Other objects and advantages of my invention will be more apparent from the following description when taken in connection with the accompanying drawings, in which:

40 Figure 1 is a view of the agitator of my invention and indicating the vat in which it is oscillated.

45 Figure 2 is a view taken on the line 2—2 of Figure 1.

50 Figure 3 is a view taken on the line 3—3 of Figure 1.

55 Figure 4 is a view of a modified form of the agitator shown in Figures 1 to 3, inclusive.

Figure 5 is a view taken on the line 5—5 of Figure 4.

Figure 6 is a view taken on the line 6—6 of Figure 4.

Figure 7 is a view taken on the line 7—7 of Figure 4.

The agitator of my invention is adapted to be mounted in a vat or tub 11 in which the clothes and washing fluid are placed. The washing vat may be of any desired shape, either square or, 10 as shown in the drawings, circular in cross section. The agitator, generally indicated by the numeral 12, is preferably mounted centrally of the vat 11 and is driven by a shaft 13 extending upwardly through the bottom of the vat. Suitable means are provided for supporting the agitator and enabling it to be driven by the shaft 13. Such means include a sleeve 16 which extends upward through the bottom of the vat concentric with the shaft 13. The preferred manner of supporting and driving the agitator of my invention is more particularly shown and described in a co-pending application of Peter Eduard Geldhof filed December 18, 1935, and which was issued into Patent No. 2,094,559, September 28, 1937. The drive shaft 13 may be driven by any suitable mechanism and from any suitable source of power, not necessary to be shown or described herein since such driving mechanism is well known in the art to which this invention applies. Preferably, the shaft is driven in an oscillatory manner so as to drive the agitator through an arc of 180 degrees, more or less, and at a speed of between fifty and sixty oscillations per minute. 20 25 30

The agitator 12 comprises a base 17 which is mounted close to the bottom of the vat and has an upwardly sloping surface 18 and a horizontal top surface 19. The base of the agitator, thus formed, is substantially a frustum of a cone. Preferably, integral with and extending upward from the base, to or above the normal surface level of cleansing fluid, is a hub or central post 21 which is preferably substantially cylindrical in shape. Near the top of the central post and marking the approximate normal surface level of 35 40 45 50 55 cleansing fluid is a substantially circular plate 22 which is preferably somewhat smaller in diameter than the base. The plate 22 may be formed integral with the central post and the base. A cap 23, of any desired shape, is mounted on the top of the central post in any suitable manner and has its lower outer circumference 24 substantially coinciding with the circumference of the plate 22. 55

On the base 17, are mounted a plurality of, in this instance five ribs or vanes 26, as shown more clearly in Figure 3. The vanes 26 are preferably rather small and rise only a short distance above the base upon which they are mounted. Their primary function is to exert a scrubbing and thread-deforming action upon the clothes when the agitator is oscillated. The vanes 26 extend outward from the center post 21, on the horizontal portion 19 of the base, in a smooth curve around the center post, and then curve downwardly on to the sloping portion 18 of the base and thence outward to the circumference thereof. There are thus formed upon the base 17 a plurality of vanes substantially spiral in appearance. Beneath the plate 22 are formed a plurality of vanes or scrubbing ribs 27 which are similar in size, shape and direction of extension and curvature to the vanes 26, that is, the plate 22 is provided with preferably five vanes 27 which spiral out from the center post 21 and curve in the same direction around the center post as the vanes 26.

Formed integral with the center post 21 and preferably mounted at approximately its mid-point is a plate 28. The plate 28 is, preferably, made substantially circular in shape and is slightly smaller in diameter than the base 17. Also preferably, the central axis of the plate 28 substantially coincides with the central axis of the agitator except that the axis of the plate 28 is tipped from the vertical so that the plane of the plate is at an angle of approximately thirty degrees to the horizontal, as shown in the drawings. Mounted both on the top and on the bottom surfaces of the plate 28 are a plurality of, preferably five, vanes or scrubbing ribs 31 and 32 which are similar to the scrubbing vanes 26 and 27. These scrubbing vanes, as shown more clearly in Figure 2, also extend outward from the center post 21 and extend spirally on the upper and lower surfaces of the plate 28.

When the agitator is oscillated at a speed and amplitude of oscillation as above indicated and with the level of the cleansing fluid approximately at the level of the plate 22, the clothes are alternately raised and depressed on two sides of the vat. For example, considering only that part of the plate 28 which lies forwardly of a diameter drawn from the point 33 to the point 34. When the agitator rotates in a counterclockwise direction, the upper surface of this half of the plate acts as an inclined plane which passes in under the clothes above the plate and raises the body of clothes upwardly in the vat. When the agitator is reversed, the under surface of the plate 28 moves through the clothes and depresses the clothes beneath the plate. The same alternate raising and depressing simultaneously occurs on the other side of the vat caused by the movement of the other half of the plate 28 through the body of clothes.

Accompanied by this upward and downward movement of the clothes, the vanes 31 and 32 move through the clothes and exert a substantial scrubbing and thread-deforming action thereon which materially aids in cleansing the clothes. Similarly, the vanes 26 and 27 exert a scrubbing action on the clothes which come in contact therewith. In order to prevent the various articles of clothing from remaining in substantially the same relative position in the vat and to insure that each article of clothing is at some time during the washing operation subjected to the scrubbing action of the vanes 26,

27, 31 and 32 and to the raising and depressing action of the plate 28, each of the vanes is curved with respect to the center post 21 spirally on the surface of the base 17, the plate 22 and the plate 28 in the same direction, that is, clockwise. The vanes are shaped so that they exert a greater thrust on the clothes and washing fluid when the agitator is rotating in the clockwise direction than when it is rotating in the counterclockwise direction. For example, the direction of curvature of the blades is such, as illustrated in Figure 2, that the leading surface 37, when the agitator is rotating in a clockwise direction, exerts a greater thrust on the clothes and washing fluid than the following surface 38 when the agitator is reversed. The resultant action is to cause the clothes and washing fluid to circulate around the vat in a clockwise direction. Thus, the vanes 26, 27, 31 and 32 serve not only the function of exerting a scrubbing action on the clothes, but also serve to cause the various articles of clothing to change their relative positions in the vat whereby, at some time during the washing cycle, each article of clothing is brought into contact with the agitator.

In Figures 4 to 7, inclusive, I have shown a modified form of the agitator illustrated in Figures 1 to 3, inclusive, wherein the base 39 is substantially horizontal with the central cylindrical post 41 extending upwardly therefrom. The plate 22, together with its scrubbing ribs 27 and the cap 23, are omitted from this form of the invention. The plate 42, similar to the plate 28 of Figure 1, extends at an angle to the horizontal. The plate 42, in this instance, is substantially square although having the corners 43 thereof slightly rounded. A rim 44 extends around the periphery of the plate 42 and is slightly wider than the thickness of the plate so as to provide a ledge 45 and 45' extending completely around both the upper and lower surfaces of the plate. Bridging the space between the uppermost corner 43' of the top surface of the plate and the center post is a member 46 which merges into the center post 41 in a smooth curve. The member 46 is preferably formed integral with the center post and has its upper surface rounded off. Between the lower surface of the plate 42 and the base and formed integral with the center post 41 are a pair of blades 47 and 48. The blades 47 and 48 are substantially vertical and extend tangentially from the outer post. They are, preferably, mounted so that they are angularly spaced from each other at less than a right angle. The blades 47 and 48 extend outward substantially to the circumference of the base 39 where they are curved, as at 49, in a clockwise direction on substantially the arc of curvature of the base thus forming hook-shaped portions 51. The outer vertical edges of the hook-shaped portions 51 are beaded, as indicated at 52, so as to prevent formation of sharp edges likely to tear the clothes.

When the agitator of this modification is oscillated, the plate 42 acts substantially the same as the plate 28 of Figures 1 to 3, inclusive, serving to alternately raise and depress the fabrics. While I have shown this agitator without scrubbing ribs, it will of course be appreciated that some form of scrubbing ribs may be used if desired, although it has been found that the ledges 45 and 45' more or less serve the function of scrubbing ribs. When the agitator is rotated in the clockwise direction, the hook portions 51 of the blades exert a substantial thrust on the

clothes and washing fluid and cause rotation of the contents of the vat in that direction. When the agitator is reversed, thrust is exerted by the surfaces 53 of the blades but the action is somewhat less violent due to the fact that the hooked portions 54 of the blades have little or no effect when the agitator is rotating in the counterclockwise direction. The hooking of the blades, therefore, causes a slight resultant movement of the clothes and washing fluid in a clockwise direction around the vat and insures that, at periodical intervals, the various articles of clothing will change their relative positions in the vat so that new clothes surfaces are constantly being presented to the action of the agitator.

While I have shown the preferred forms of my invention, it will be apparent that various modifications and changes may be made in the form and relation of the parts of the agitators without departing from the spirit of the appended claims.

I claim:

1. An agitator adapted to be mounted for oscillation in a vat containing clothes and washing fluid, said agitator having a central post extending substantially from the bottom of the vat to the normal surface level of cleansing fluid and constituting an axis of oscillation for the agitator and having a substantially flat plate mounted on the central post at approximately the mid-point of the post, said plate being of substantial area and being mounted at an angle to the horizontal whereby when the agitator is oscillated the clothes are alternately raised and depressed, and said plate having a plurality of scrubbing ribs mounted thereon, each of said scrubbing ribs being curved on the surface of the plate in the same direction.

2. An agitator adapted to be mounted for oscillation in a vat containing clothes and washing fluid, said agitator having a central post constituting an axis of oscillation for the agitator and having a substantially flat plate mounted on said central post at approximately its mid-point, a base for the agitator mounted close to the bottom of the vat, and means integral with the agitator configurated so as to circulate the clothes in one resultant circulatory direction when the agitator is oscillated.

3. An agitator adapted to be mounted for oscillation in a vat containing clothes and washing fluid, said agitator having a base mounted in close proximity to the bottom of the vat, a central post extending upwardly from said base to substantially the normal surface level of cleansing fluid, an agitating element mounted on said central post at approximately half the normal depth of cleansing fluid, said agitating element being of substantial area and being mounted at

an angle to the horizontal whereby when the agitator is oscillated the clothes are alternately raised and depressed, said base and agitating element being substantially smaller in diameter than the diameter of the vat whereby to form a space around the agitator for receiving and circulating the clothes, and means integral with the agitator and configurated so as to circulate the clothes and washing fluid in one resultant circulatory direction around the vat.

4. An agitator adapted to be mounted for oscillation in a vat containing clothes and washing fluid, said agitator having a base mounted adjacent the bottom of the vat, a central post extending upward from the base, a top plate mounted on said post at substantially the normal surface level of cleansing fluid, and a plate mounted substantially midway of said post, said plate being mounted at an angle to the horizontal and having scrubbing ribs on both sides thereof.

5. An agitator adapted to be mounted for oscillation in a vat containing clothes and washing fluid, said agitator having a base mounted adjacent the bottom of the vat, a central post extending upward from the base, a top plate mounted on said post at substantially the normal surface of cleansing fluid, a central plate mounted substantially midway of said post, said central plate being mounted at an angle to the horizontal, and scrubbing ribs mounted on the top surface of said base, the under side of said top plate and on both sides of said central plate.

6. An agitator adapted to be mounted for oscillation in a vat containing clothes and washing fluid, said agitator having a base mounted adjacent the bottom of the vat, a central post extending upward from the base, a plate mounted substantially midway of the post, said plate being mounted at an angle to the horizontal, said base and agitating element being substantially smaller in diameter than the diameter of the vat whereby to form a space around the agitator for receiving and circulating the clothes, and a plurality of blades extending between said base and said plate.

7. An agitator adapted to be mounted for oscillation in a vat containing clothes and washing fluid, said agitator having a base mounted adjacent the bottom of the vat, a central post extending upward from the base, a plate mounted substantially midway of the post, said plate being mounted at an angle to the horizontal, and a plurality of blades extending between said base and said plate, each of said blades extending outward on the base substantially to the circumference thereof and having at least their outer ends curved in horizontal cross section.

JABEZ CURRY NELSON.
